UNITED STATES PATENT OFFICE.

OSCAR GASSETT, OF BOSTON, MASSACHUSETTS.

APPARATUS FOR THE DISTRIBUTION OF ELECTRICITY.

SPECIFICATION forming part of Letters Patent No. 310,665, dated January 13, 1885.

Application filed June 2, 1884. (No model.)

To all whom it may concern:

Be it known that I, OSCAR GASSETT, of Boston, county of Suffolk, and State of Massachusetts, have invented an Improvement in Distribution of Power, of which the following description, in connection with the accompanying drawing, is a specification, like letters on the drawing representing like parts.

My invention relates to apparatus for supplying power derived from a prime motor at a main or distributing station for the production of electricity at various sub-stations. The prime motor is employed to store power preferably by accumulating a fluid under pressure, which fluid is conveyed by pipes to the various sub-stations where the electricity is to be generated. At each of these sub-stations there is a secondary motor adapted to be actuated by the power stored by the prime motor, and the application of power to the secondary motor is controlled by an electro-magnet and circuit having a suitable switch or circuit-controlling device, which may be located at any desired point, so that by operating the said switch the secondary motor is set in operation and the generation of electricity begins.

The drawing shows in diagram an apparatus for distributing power embodying this invention, the electricity generated being shown as employed for lighting.

The prime motor at the main or power-supplying station may be of any suitable character, as a wind or water wheel or steam-engine, the crank *a* of which only is shown as actuating a pump or compressing device, *b*, by which air or other fluid is accumulated under pressure in a main receptacle or tank, *c*, having a distributing-pipe, *d*, by which the said fluid is conveyed to the various points where the power is to be used. At such points or sub-stations where the power is to be used the pipe *d* is provided with branch pipes *d'*, preferably having connected with them secondary tanks or receptacles *d''*, containing the fluid under pressure, there being check-valves *d''* between the said main pipe and secondary reservoirs, *d''*. The pipe *d'* enters a controlling device, (shown as a chest, *e*,) having ports *f*, *g*, the former leading to a main valve cylinder, *h*, and the latter to a controlling valve chamber, *i*, separated from the said main cyl-

inder *h* by a partition, *k*, having a passage, *k'*, controlled by the governing-valve, *m*, which is operated by an electro-magnet, *n*, controlling 55 the flow of fluid from the chamber *i* to the cylinder *h*, where the said fluid actuates the main valve, having a transverse port or annular groove, *o'*, which, when the said valve is in the proper position, as shown in the drawing, connects the port *f* with the port *f'*, leading to the pipe *d'*, which supplies the fluid for actuating the secondary motor *d''*. The chamber *i* is constantly supplied through the port *g* with fluid under proper pressure, when permitted to pass through the passage *k'*, to move the valve *o* against the pressure of a spring, *p*, into the position to admit the fluid to the pipe *d'* and motor *d''*. The valve *o* is provided with a small passage, *o''*, or has a loose fit in the cylinder *h*, thus permitting the fluid to escape from the said cylinder *h*, but not with sufficient rapidity to materially reduce its pressure as long as it is freely admitted through the passages *g* and *k*. When, however, the valve 75 *m* is closed and the supply of fluid thus cut off from the cylinder *h*, it quickly escapes from the said cylinder, permitting the spring *p* to force the valve *o* toward the partition *k* until the ungrooved portion of the said valve closes 80 the port *f*, and thus cuts off the supply of fluid from the motor *d''*. The valve *m* is moved to open or close the passage *k'*, and thus govern the position of the main valve *o* by the electro-magnet *n*, included in the circuit *n'*, having a circuit-controlling device or switch, *n''*, by which the said circuit may be opened or closed to govern the condition of the magnet *n*, which, as shown in this instance, retains the valve *m* open when the said magnet is energized or while its circuit is kept closed. The secondary motor *d''* actuates an electric generator, *r*, which thus produces a current of electricity whenever the switch *n''* is closed, and ceases to operate when the said switch is 95 opened; and the current generated may be employed for any desired purpose, being shown in this instance as supplying a lamp, *t*, the light of which is thus controlled by the switch *n''*.

When, as will generally be the case, there 100 are a number of sub-stations supplied from one prime motor, the latter may be run practically constantly to supply sufficient power to operate the secondary motors and generators

when needed, the said power being stored in the main and secondary reservoirs *c d* until needed, and the said storage will enable the secondary motors to be run during portions 5 of the time with a greater consumption of power than could be supplied by the prime motor if the power were used directly therefrom without accumulation.

I claim—

- 10 1. The combination of a prime motor for storing power, a secondary motor adapted to be actuated thereby, an electric generator actuated by the said secondary motor, and an electro-magnet, circuit, and circuit-controlling device governing the application of power to the secondary motor, substantially as described.
- 15 2. The combination of a prime motor, op-

erating to accumulate a fluid under pressure, a main reservoir for said fluid, and distributing-pipes leading therefrom, secondary reservoirs connected with said pipes at sub-stations where the power is to be used, secondary motors and electric generators actuated thereby at the said sub-stations, and electro-magnets, circuits, and circuit-controlling devices governing the application of power to the secondary motors, substantially as described.

In testimony whereof I have signed my name 30 to this specification in the presence of two subscribing witnesses.

OSCAR GASSETT.
